UNITED STATES PATENT OFFICE.

JAMES F. CONNOR, OF CLEVELAND, OHIO, ASSIGNOR OF ONE-HALF TO FRED S. HOFFMAN, OF YOUNGSTOWN, OHIO.

CUFF LINK.

Application filed January 24, 1924. Serial No. 688,268.

To all whom it may concern:

Be it known that I, JAMES F. CONNOR, a citizen of the United States, residing at Cleveland, in the county of Cuyahoga and State of Ohio, have invented certain new and useful Improvements in Cuff Links, of which the following is a specification, reference being had to the accompanying drawings.

10 This invention relates to an improved cuff link of the type in which a pair of studs are provided, one for fitting into each of the buttonholes of a cuff, and one object of the invention is to provide improved 15 means for connecting the studs or links so that these studs may be yieldably held in close engagement with each other but moved apart so that in washing the hands or doing any other work which requires the cuffs 20 and shirt sleeves to be drawn upwardly upon the arms, the studs may be moved apart and permit the cuff to be easily moved upwardly upon the arm and then returned toward each other when the cuff is again 25 moved downwardly to the normal position.

Another object of the invention is to so connect the links that when the cuff is drawn upwardly upon the arm, the studs may be still drawn toward each other so 30 that the cuff will be drawn about the upper portion of the arm and frictionally held against sliding downwardly.

Another object of the invention is to so construct the studs that the cord or other 35 flexible element which connects the studs may be wound upon a drum positioned in the head of one of the studs and yieldably held against rotation when unwinding the cord during movement of the studs away 40 from each other.

Another object of the invention is to so construct the drum and head portion of the stud in which the drum is mounted that the drum may freely rotate within the limits 45 permitted by the spring and the cord be guided in its movement into and out of this stud and prevented from being liable to be caught and held against sliding movement.

50 This invention is illustrated in the accompanying drawings, wherein:—

Figure 1 is a view showing the improved cuff button in side elevation;

Figure 2 is an enlarged sectional view through the cuff button;

Figure 3 is a transverse sectional view taken along the line 3—3 of Figure 2;

Figure 4 is a top plan view of the drum mounted in the outer head of one of the links;

Figure 5 is a side elevation of the spindle which rotatably mounts the drum;

Figure 6 is a transverse sectional view through the spindle;

Figure 7 is a fragmentary perspective view of a portion of the drum and showing the manner of forming the spring engaging prong.

The improved cuff button is provided with a pair of studs 1 and 2, which are to be 70 positioned in the buttonholes of the cuff, with the neck portions 3 extending through the buttonholes, the heads 4 positioned against the outer faces of the cuff, and the smaller heads 5 positioned against the inner faces of the end portions of the cuff and in contact with each other when the cuff is in the normal position about the wrist of the wearer. These studs in some ways resemble cuff buttons which are now 80 in use, but instead of being releasably attached at their inner ends by snap fasteners and being entirely separable, they have been provided with an improved means for connecting them but permitting them to be 85 moved away from each other.

The stud or link 1 will now be described, as this is the stud which carries the drum and cord which connects the stud 2 with the stud 1. This stud 1 has its head 4 provided with a cup-shaped body portion 6 which is carried by the neck 3 and is provided with an annular wall 7 about which fits the annular wall or flange 8 of the cap 9. The cup 6, together with the neck 3 90 and smaller inner head 5, may be formed of a strong but relatively cheap material, and the cap may be formed of gold or other valuable metal and may be ornamented in any manner desired. It will thus be seen 95 that the cuff buttons may be made to sell at different prices in accordance with the

value of the cap, but that in all cases the cup 6, neck 3, and inner head 5 will preferably be formed of the same kind of material. This cup 6 is provided with an upstanding rib 10 which extends for substantially the entire circumference of the cup but has its ends terminating in spaced relation to provide a space 11 through which the cord to be hereinafter more specifically mentioned may pass. The wall 7 has been cut to provide upper and lower tongues bent inwardly and toward each other and preferably curved transversely, thereby providing a guide 12 which is positioned at a point opposite the space 11 between the ends of the rib 10. This guide serves to direct the cord from the drum carrying it toward the bottom of the cup so that it may be led through the space between the ends of the rib.

The drum 13 which carries this cord is positioned in the cup 6 upon a spindle 14 which fits into the neck 3, and this drum rests upon the rib 10 so that it will be supported properly and caused to turn easily when the cord 15 is being unwound from the drum or wound upon the drum. The spindle 14 which rotatably mounts the drum fits into the hollow neck 3 of the stud and is provided with a groove 16 leading from its inner end and communicating with an opening 17. Therefore, when the stud is thrust into this neck, the lug 18 which extends inwardly from the outer end of the neck 3 may pass through the groove 16 and into the opening 17. This lug and groove will, therefore, serve to insure proper positioning of the spindle 14 in the neck and will also serve to prevent the spindle from rotating in the neck. A tongue 19 has been cut longitudinally from the body portion of this spindle and is bent inwardly and curved transversely to provide a guide along which the cord 15 passes. It will thus be seen that this cord, after being wound upon the drum, may be engaged with the guide 12 and then directed toward the spindle beneath the drum and through the space 11 between the ends of the rib 10 and passed through the opening 20 formed in the spindle when cutting the tongue 19 and then projected through the neck 3 in engagement with the guide 19 and out of the stud through an opening 21 formed in the head 5 of this stud. The projected end portion of the cord will then be passed through a corresponding opening 22 formed in the head 5 of the stud 2 and knotted, as shown at 23, so that this knotted end cannot pass outwardly through the opening 22. This knot will, of course, be formed before the cap 24 is placed upon the body portion of the outer head 4 of this stud 2.

It is desired to have the cord normally wound upon the drum and, therefore, there

has been provided a coiled spring 25 which is positioned within the drum about the spindle. The inner end of this spring 25 fits into a slot 26 formed in the opposite end portion of the spindle from the groove 16 and will be prevented from passing out of this slot when tension is applied to the spring. The outer end of the spring is provided with a loop 27 which fits upon a prong 28 cut from the bottom of the drum 13 and bent to extend at right angles thereto. This prong is provided with a hook 29 at its free end so that while the loop 27 may be easily placed about this prong, it cannot readily slip off of the prong.

After the spindle 14 has been put in place, the cord will be threaded through the openings formed by the guide 12 and then led along the bottom of the cup and passed through the opening 20. The cord will then be passed through the neck and opening 21 in the head 5 and through the opening 22 in the head 5 of the second stud or link and formed into a knot. The drum having the cord attached to it will then be put in place upon the spindle within the cup and will be rotated so that the cord will be wound upon this drum. After the cord has been wound upon the drum, the spring can then be put in place with its inner end secured in the slot 26 formed in the spindle and its outer end will be connected with the prong 28. The cap 24 can then be put in place about the annular wall of the cup 6 and the cap 24 put in place about the cup of the other stud. The cuff button is then ready for use.

When this cuff button is in use, the heads 4 will be passed through the buttonholes and the inner heads 5 will be in engagement with each other between the end portions of the cuff. Under normal conditions, the studs or links will remain in contacting engagement with each other. When, however, it is desired to draw the sleeves upwardly upon the arms so that the cuffs will not become soiled when washing the hands or doing any work which is liable to soil the cuffs, such as making repairs to an automobile or the like, the sleeves can be simply drawn upwardly upon the arms and as they move upwardly the studs or links will be drawn apart and the cord drawn out of the stud 1. As this cord is drawn out of the stud it will, of course, be unwound from the drum and as the drum rotates during unwinding of the cord, the spring will be wound about the spindle and thus placed under tension so that it causes a pull upon the cord which will serve to hold this cord tight and thereby draw the end portions of the cuff toward each other and hold the cuff in close engagement about the upper portion of the arm. Therefore, the cuff will be held in frictional engagement with the arm and will not be

liable to slip downwardly. When the cuff is again returned to the normal position about the wrist, the downward movement of the cuff permits the spring to unwind and rotate the drum so that the cord is wound upon the drum and the studs or links drawn toward each other until they are again in contacting engagement with each other. It will thus be seen that with this construction 10 the links or studs will be normally held in close engagement with each other but will be permitted to move apart an amount controlled by the length of the cord and the extent to which the spring may be wound.

It will be further noted that the cord is so guided that it cannot become caught and prevented from properly passing out of or into the link 1. It will be also noted that 20 the spindle is so mounted that it will be prevented from being rotated in the neck 3, and further that it can only be put in place in such a position that the opening 20 and guide 19 will be properly positioned to receive and engage the cord 15.

I claim:—

1. A cuff button comprising separate links, a drum rotatable in one link about the longitudinal axis thereof and spring held 30 against rotation in one direction, and a cord wound upon said drum and carried out of the link and connected with the other link to normally hold the links in contacting engagement with each other.

2. A cuff button comprising separate links, each having a hollow head, a flexible connection between said links to limit movement of the links away from each other, and spring actuated means for normally drawing 40 said flexible means into the head of one of the links and retaining the links normally in contacting engagement with each other.

3. A cuff button comprising separate links, each having inner and outer heads and a neck connecting the heads, a drum rotatably mounted in the outer head of one of said links for rotation about the axis thereof, a cord wound upon said drum and 50 projected through the neck and inner head of the link and connected with the inner head of the other link, and spring means yieldably holding said drum against rotation in one direction to normally hold the cord wound upon the drum with the inner heads of the links in contacting engagement with each other.

4. A cuff button comprising separate links, each having inner and outer heads 60 and a neck connecting said heads, a hollow spindle fitting into the neck of one link and extending into the outer head thereof, a drum rotatably fitting upon said spindle within the outer head of the link, a cord wound upon said drum, said spindle having

a side opening between the drum and neck, a guide carried by the wall of the outer head, the cord being engaged with said guide and directed through the opening of said spindle and through the neck and inner 70 head of the link and connected with the inner head of the other link, and a spring positioned in said drum about the spindle and having its inner end connected with said spindle and its outer end connected with said drum to yieldably hold the drum against rotation in a direction for unwinding of the cord.

5. In a cuff button comprising separate links, one having an inner head, an outer head, and a neck connecting the heads, a cap for the outer head, a spindle fitting into said neck and extending into the outer head and having a tongue cut therefrom and bent inwardly to provide a guide within the portion of the spindle fitting in the neck, the wall of the outer head having tongues cut therefrom and bent inwardly to provide cord-receiving openings and cord guiding means between the openings, a drum supporting rib extending from the bottom of the outer head into the same and positioned about said spindle with its ends terminating in spaced relation to provide a cord passage between the cord guide of the outer head 95 and the cord receiving opening and guide of the spindle, means for holding the spindle against rotation in the neck, a drum fitting upon the spindle in the outer head and resting against said rib, a cord wound upon the drum and passed about the cord guide carried by the outer head and extending through the space between the ends of the rib and through the opening in the spindle and then engaged with the guide within the 100 spindle and passed through the spindle and neck and inner head of the link and connected with the inner end of the second link, and a coiled spring positioned in the drum about the spindle with its inner end connected with the spindle and its outer end connected with said drum to yieldably hold the drum against rotation in a direction for 105 unwinding of the cord therefrom.

6. A cuff button comprising separate links, one being hollow and having a neck portion, a head at the outer end of the neck portion, a spindle fitting into said neck and extending into the head and having its inner end portion provided with a longitudinally extending groove, a lug receiving opening at the inner end of the groove, a lug extending inwardly from the wall of the neck for passing through the groove and fitting into the opening to hold the spindle 115 against rotation, said spindle having a side opening adjacent the bottom of the head when the spindle is in place and having its outer end portion provided with a slot for receiving one end of a spring, a drum 120 receiving one end of a spring, a drum 125 receiving one end of a spring, a drum 130

tatably mounted upon the spindle within the head, a cord wound upon the drum and passed through the side opening in the spindle and through the neck and inner end of the link and connected with the inner end of the second link, a prong extending from the bottom of said drum and extending toward the outer end thereof, a coiled spring positioned within the drum about the spindle and having its inner end engaged in the

slot formed in the outer end portion of the spindle and its outer end engaged with said prong to yieldably hold the drum against rotation in a cord unwinding direction, and a cap carried by the head and closing the outer end thereof. 15

In testimony whereof I hereunto affix my signature.

JAMES F. CONNOR.
